(57) **CLAIM**

The ornamental design for a lighting signature, as shown and described.

DESCRIPTION

FIG. 1 is a front view of a lighting signature with a first lighting signature element;

FIG. 2 is a front view of a lighting signature with the first lighting signature element and a second lighting signature element; and,

FIG. 3 is a rear view of the first lighting signature element shown in an opening of a vehicle component.

Portions of the figures shown in diagonal lines are for illustrative purposes only and form no part of the claimed design.
